PROCESS FOR CONVERTING HYDROCARBON OILS

Donald H. Mace, Upper Montclair, N. J., assignor to The Texas Company, New York, N. Y., a corporation of Delaware

Application May 2, 1932, Serial No. 608,614

6 Claims. (Cl. 196—48)

This application is a continuation in part of my copending application Serial Number 26,572 filed April 29, 1925 for Process and apparatus for converting hydrocarbon oils.

5 This invention relates to the conversion under pressure of high boiling hydrocarbon oils into lower boiling products, and has special reference to a conversion process and apparatus of the so-called "coil and drum" type, in which the oil is 10 decomposed or cracked by rapidly raising the temperature thereof in transit through a heating coil and then delivering it into an enlarged drum or chamber in which cracking temperatures and pressures are maintained.

15 One of the objects of the invention is to provide a process and system of this general character in which the bulk of the heat employed for the cracking operation is imparted to the oil in transit through the heating coil, while the maintenance 20 of the desired cracking temperature in the drum or chamber is effected through the addition of relatively small quantities of heat through the introduction into the body of hot oil therein of highly heated hydrocarbon vapors and gases, hydrogen, or other vaporous or gaseous mediums.

25 Another object of the invention is to provide a combined liquid-vapor phase cracking process and apparatus in which the bulk of the heat is imparted to a flowing stream of liquid oil in 30 transit through a heating coil and the highly heated oil delivered into a heat-insulated drum in which the vapors and gases from a vapor phase cracking operation are introduced for the purpose of either slightly raising the temperature 35 of the liquid body therein to the desired cracking temperature or maintaining the desired cracking temperature therein by compensating for heat losses incident to radiation, decomposition, distillation, etc.

40 More specifically, it is an object of the invention to minimize and practically eliminate the usual carbon difficulties resulting from oil cracking or decomposition by regulating the rate of heating the oil in transit through the heating coil 45 so as to bring it to a cracking temperature at substantially its exit from the coil whereby the time element is so controlled as to avoid any substantial degree of cracking within the coil, and thereafter delivering the oil into a heat-insulated drum where the desired cracking temperature is sustained by the continuous admission 50 of highly heated vaporous and gaseous products, preferably although not necessarily, from a vapor phase cracking operation. In this way no appreciable amount of carbon is even formed in the

heating coil, while such carbon as is produced by concentrated cracking in the drum is of such a character and is so thoroughly held in suspension in the vigorously agitated oil therein that it may be handled with facility without serious caking 5 upon the unheated walls thereof.

Another object of the invention is to provide a combined liquid-vapor phase cracking process and system of the "coil and drum" type in which the final product of the commingled vapors 10 evolved from the liquid phase and the vapor phase cracking operations shall retain the beneficial qualities of both classes of conversion processes, whereby the advantageous slow burning and anti-knock properties of unsaturated vapor phase 15 cracked products may be combined with the well-known desirable qualities of liquid phase cracked products in sufficient proportions to produce a gasoline-like fuel of superior character for internal combustion engines.

20 Still another object of the invention is to provide an oil conversion process of the coil and drum type in which a close regulation of the cracking temperatures in the drum, or plurality of series-connected drums, may be obtained by 25 automatically or otherwise regulating the amount or degree of auxiliary heat supplied thereto through highly heated vapors or gases from an external source—preferably from a vapor phase cracking operation—in response to variations in 30 temperature of the oil in said drum or in said individual drums.

35 A still further object of the invention is to provide a combined liquid-vapor phase cracking process of the above indicated character in which the heavier constituents of the commingled and combined evolved vapors are separated out and returned, while still hot, to serve as a supply of clean distillate for the vapor phase cracking operation, thereby avoiding the necessity of a preliminary distillation which is usually requisite for producing a charging stock of suitable quality for vapor-phase conversion. The process, therefore, operates after normal conditions are established, to supply oil of suitable character for 40 its own operation in the vapor phase stage. Any excess of such clean distillate may be cyclically returned to the main heating coil for retreatment.

45 The clean distillate may also include or consist solely of gasoline fractions suitable to be reformed by cracking to increase the anti-knock value thereof. If desirable other gasoline fractions to be reformed may be supplied from an external source in conjunction with or in place 50 of the distillate mentioned.

55

These and other objects of my invention, and the features by means of which they are attained, will be more fully understood from the following description of the process in connection with the preferred embodiment of the apparatus illustrated in the accompanying drawings, in which:—

Fig. 1 is a diagrammatic view of an apparatus or system constructed in accordance with the present invention and adapted for practicing my improved cracking process, and

Fig. 2 is a diagrammatic view of a modified form of apparatus or system likewise embodying the novel features of my invention.

Fig. 3 is a diagrammatic view of another modified form of system embodying novel features of my invention.

Referring to the drawings, and for the present more particularly to Fig. 1, the system comprises, in general, an elongated heating coil 12 of restricted cross section for heating the oil in transit to a cracking temperature; a heat insulated drum or still 10 for receiving the highly heated oil from the coil 12; an auxiliary converter 14, preferably comprising an elongated cracking coil or tube, of restricted cross section and adapted to crack the oil supplied thereto in the vapor phase and to deliver the resulting highly heated evolved vapors and gases into the body of hot oil in the drum 10 whereby the oil in the still is either raised to or maintained at an effective cracking temperature for the conversion of the oil in the liquid phase, a separator 16 for receiving the combined evolved vapors from the drum 10 and selectively condensing out the heavier constituents thereof, while allowing the lighter constituents of desired volatility to pass on; a condenser 18 for condensing the lighter constituents of the vapors, and a collecting tank 20 for receiving the ultimate light distillate.

The drum 10 may be of any suitable construction and is heat insulated by means of lagging 21. It is provided with a residue draw-off pipe 22 having a valve 23. The drum is not heated externally and the body of already hot oil delivered thereto receives added heat solely from the vapors and gases evolved in the vapor phase cracking converter 14, which vapors are conducted by means of a heat insulated pipe 24 into the lower part of the still 10 against a deflector 25 by means of which the hot vapors are evenly distributed throughout the drum. The heat insulated pipe 24 is provided with a pressure valve 26 for controlling the passage of vapors therethrough and regulating the pressure on the converter 14.

The heating coil 12 preferably comprises an elongated coil of restricted cross section that is heated by the products of combustion from a suitable furnace 28 disposed below it. The temperature of the oil emerging from the exit of the heating coil may vary between 700-900° F. but is more frequently maintained at approximately 800° F. A pressure upwards of 80 pounds may be maintained at the coil exit and in the drum, depending upon operating conditions and the character of the stock being treated. Ordinarily, however, a pressure of approximately 100 to 150 pounds will be found suitable for a gas oil charging stock. The heating coil 12 is connected by means of an insulated pipe 29 with the still at a suitable point intermediate its ends. The heated oil is delivered into the drum 10 through an extension of the pipe 29 and against a deflector 31 whereby the oil is distrib-

uted evenly in the still. The separation of the distributing deflectors 25 and 31 functions to thoroughly agitate the oil and keep the carbon in suspension. The heating coil 12 is continuously supplied with a heavy oil, such for instance as paraffine gas oil, from a suitable source and the oil is forced into the heating coil 12 by a pump 32 through a charging line 33 which is connected to the inlet end of the coil. Other oils may, of course, be used and paraffine gas oil is specified merely for illustrative purposes as showing a particular oil which may be satisfactorily employed.

The auxiliary vapor phase converter 14 may be of any type suitable for vapor phase conversion and as illustrated is of a form similar to that of the heating coil 12 and comprises an elongated coil of restricted cross section that is highly heated by means of a furnace 35 disposed below it. The converter 14 is supplied under pressure with oil of a suitable character from a convenient source and the oil is forced into the coil by a pump 36 through a charging line 37 having a valve 38. For vapor phase conversion, the oil must be relatively clean and, therefore, until the normal operating conditions are established, a preliminary distillation of a suitable oil, such for example as paraffine gas oil, may be resorted to in order to produce an oil having desirable characteristics for this purpose.

As the oil is forced under pressure through the cracking coil 14 at a rapid rate, it is subjected to high cracking temperatures varying from 900° to 1300° F. and is cracked in the vapor phase. The pressure within the cracking coil 14 will exceed somewhat that being utilized in the drum 10 for the liquid phase cracking operation. The vapor phase conversion operation is not confined to these temperatures and pressures and may vary therefrom to a considerable extent, depending upon the character of the oil being treated and other operating conditions. The vapors and gas evolved in the cracking coil 14, including the converted and unconverted vapors, emerge therefrom at very high temperatures and are conducted through the heat insulated pipe 24 and delivered directly into the body of already highly heated liquid oil in the drum 10. The heat of the vapors and gas thus introduced into the still is utilized either to raise the body of hot oil therein to the desired effective cracking temperature or to maintain it at such cracking temperature to bring about the conversion of the oil in the liquid phase without the necessity of supplying external heat to the drum. The temperature in the still, after the normal operation of the system has been initiated, is maintained at 700 to 900° F. although it may vary therefrom. At a temperature of 800° F. or somewhat less, the body of liquid oil in the drum will be converted at a satisfactory rate.

Thus it is apparent that the bulk of the heat is supplied to the oil while in the heating coil 12 and that hot gases and vapors are injected into the highly heated oil in relatively small quantities for the purpose of maintaining constant or regulating the cracking temperature of the already highly heated oil in the drum, and for compensating for heat losses occasioned by radiation and decomposition, or by distillation, provided the drum is used for distillation, as is usually considered preferable. It is in the drum that the bulk of the cracking or decomposition is effected,

although a portion thereof may be carried on in the heating coil 12 if desired.

Ordinarily, however, I consider it advisable to so regulate the temperature of the heating coil 10 with respect to the rate of flow of the oil through the coil 12 that the oil in transit only reaches a suitable and effective cracking temperature substantially at the exit of the coil. The time element of cracking is thus controlled so 10 that no material amount of cracking takes place in the heating coil. By reason of such careful regulation, no appreciable carbon can be formed in the coil. Hence, deposition of carbon, with attending local hot spots and clogging of the coil, 15 is prevented. In the drum, however, the desired cracking temperature is sustained in the manner set forth, and because of the ample volume of the drum, the oil remains under cracking conditions for a sufficient period for the desired degree of 20 cracking to transpire. The drum, being unsub- jected to external heat and held at the desired cracking temperature solely by the heat of the vapors and gases from the vapor phase converter 14, which continually keep the body of oil in con- 25 stant and vigorous agitation, the carbon accumu- lating therein as a result of cracking is of such character that it may be easily withdrawn with the residual oil and does not cake upon the un- heated walls of the drum to an objectionable de- 30 gree.

In order that the body of oil in the drum 10 may be maintained at a substantially constant predetermined cracking temperature, provision is made for automatically regulating the tempera- 35 ture of the vapors and gases introduced therein— preferably from the vapor phase cracking opera- tion. For this purpose a thermocouple 39 is po- sitioned in the wall of the still with its inner end projecting into the body of heated oil therein. 40 When the temperature decreases or increases be- yond predetermined limits, the thermocouple acts to operate a suitable automatic valve-actuating mechanism 40 which is connected with the fuel supply line 41 of the furnace 35 through which 45 fuel is supplied to the burner 42, whereby the supply of fuel to the burner 42 is automatically increased or decreased, as may be required. Ac- cordingly, the temperature of the heated vapors and gases introduced into the still 10 is raised 50 or lowered sufficiently to maintain the body of oil in the still at a substantially constant pre- determined temperature. Of course, the charging rate of the converter might be regulated in order to vary the temperature of the cracked vapor 55 phase products, if desired, or in any suitable means of regulating the temperature or amount of vaporous products delivered into the drum may be employed.

The intermingled vapors evolved from the liquid 60 phase cracking operation in the drum 10, together with those of the vapor phase cracking operation in the converter 14, are preferably withdrawn from the still through an insulated vapor line 43 and are conducted to the separator 65 16, wherein a separation of the lighter and heavier constituents is effected. The lighter constituents of desired volatility emerge from the upper end of the separator 16 and pass through a pipe 44 into the water-cooled condenser 18 in 70 which the vapors are condensed. The condensed distillate is then discharged and collected in the receiving tank 20 which is connected to the con- denser by a pipe 46. The receiving tank 20 is provided with a gas outlet 47 having a valve 48 and a discharge outlet 49 having a valve 50, by

means of which the operating pressure of the system is regulated and maintained.

The heavier constituents of the vapors are condensed in the separator 16 and this hot condensate is conducted through an insulated pipe 51 to a suitable pump 52 (preferably a surge pump) by which it is forcibly returned while still hot to the system. This cyclic return of condensate may be through an insulated pipe 53, having a valve 54, which connects with the charg- 10 ing line 37 of the vapor phase converter 14, or through an insulated branch pipe 55, having a valve 56, which branch pipe connects with the charging line 33, of the heating coil 12. Thus, by closing valve 56 and opening valve 54, the 15 clean condensate from separator 16 is pumped back through the pipe 51, pump 52, pipe 53, and line 37 to the vapor phase converter 14 in which it is again used as the oil supply, or to supplement an extraneous supply, for the vapor phase con- 20 version. If the amount of condensate returned from the separator 16 is too great to be conveniently handled by the converter 14, the valve 56 in the branch pipe 55 may be opened to permit a portion, at least, of the condensate to be 25 forcibly recharged into the heater 12 by the pump 52.

After the process has been brought up to normal operating conditions, the condensate pro- 30 duced in the separator 16 may be of sufficient quantity to be utilized to entirely replace the clean distillate originally supplied to the con- 35 verter 14, as hereinbefore described. In this way the process, after normal operating conditions are established, produces its own supply of clean 35 distillate of a character suitable for the vapor phase cracking operation, so that the auxiliary supply of clean distillate may be either discontinued or substantially reduced. Of course, if necessary, a small amount of preliminarily 40 cleaned distillate may at any time be charged into the converter 14 through the pipe 37.

In one of its aspects, the invention is inde- 45 pendent of the utilization of vapor phase cracked products for the heat regulation of the cracking drum, inasmuch as the temperature control of the operating conditions therein may be effected by hot hydrocarbon vapors and gases, hydrogen or other vaporous gaseous medium from an ex- 50 traneous source. However, it is deemed espe- 55 cially advantageous to operate a combined liquid-vapor phase process so that the slow-burning anti-knock properties of unsaturated vapor phase cracked products may be coupled with the bene- 60 ficial properties of liquid phase cracking in such proportions as to produce a particularly desirable and superior motor fuel for internal combustion engines. Moreover, by carrying on the combined liquid-vapor process in the manner described, the 65 characteristics of the ultimate distillate are be- 70 lieved to be considerably improved by reason of chemical reaction between the intermingled vapors of the vapor phase and liquid phase cracking operations during the treatment.

The modified form of my invention as illus- 65 trated in Fig. 2 is similar in many respects to that illustrated in Fig. 1, except that instead of a single cracking still or drum, a plurality or bat- 70 tery of series-connected insulated stills are em- ployed. The several drums or stills 60, 61, 62, 70 and 63 constituting the battery are connected by means of vapor lines 64 and liquid level lines 65. Each of the stills is provided with a residue draw- 75 off line 66 controlled by a valve 67 and all of the draw-off lines connect with a common discharge

pipe 68. The stills are not externally heated but are covered with suitable heat-insulating material to conserve the heat within.

The first still 60 of the series is connected with the heating coil 12 by the insulated pipe 29, as was the single still 10 illustrated in Fig. 1 and already described. Similarly, the coil of the vapor phase converter 14 is connected to an insulated pipe 24 having branches 69, 70, 71 and 72 connected severally with stills 60, 61, 62 and 63, respectively, and each of the branch lines is controlled by a valve 13.

The operation of the modified form of my invention is in most respects like that described in connection with Fig. 1, except that the highly heated oil from the heating coil 12 enters the first still 60 of the battery and overflows through liquid level lines 65 into the succeeding stills. The gases and vapors evolved in the vapor phase cracking operation are introduced into the several stills through the insulated line 24 and its branch pipes 69, 70, 71, and 72, in quantities sufficient to maintain the heated oil in the several stills at the desired cracking temperatures, or to raise the temperature of the oil in the stills to the desired cracking temperatures.

By means of the valves 13 in the several branch lines 69, 70, 71 and 72, independently regulated quantities of hot vapors may be introduced into any one or all the stills to maintain them at the cracking temperatures determined upon. Obviously, the operation of these valves may be rendered individually automatic by providing the several stills with temperature-regulating devices as described in connection with Fig. 1, or if preferred, a single such device may be employed to operate all the valves concurrently, or to regulate the supply of fuel to the burner 42 of the vapor phase cracking converter.

The vapors and gases resulting from the combined liquid-vapor phase cracking operations, pass from the several stills through the insulated vapor line 43 to the separator 16 wherein a separation of the heavy and lighter constituents takes place, the lighter constituents being conducted through the condenser 18 and collected in the tank 20 as the ultimate light distillate. The heavy constituents are pumped back either to the vapor phase cracking coil 14 or to the heating coil 12 as already described.

The system shown in Fig. 3 is the same as that of Fig. 1, with the addition of a second separator and auxiliary pipe lines and valves. In Fig. 3 reference numeral 76 indicates a second separator connected to the vapor pipe 44 of separator 16 by means of conduit 77 having a shut off valve 78. This conduit is adapted to pass vapors from the vapor pipe 44 of the first separator 16 into the lower part of a second separator 76, wherein the vapors are subjected to condensation resulting in the liquefaction of the heavier constituents thereof such as gasoline fractions suitable for reformation.

A valve 79 is furnished for preventing the passage of vapors from separator 16 to condenser 18 when it is desired to use also the second separator 76, and a pipe 80 having valve 81 serves to conduct vapors from the second separator to the pipe 44 leading to the condenser. Condensate from the separator 76 may be passed through pipe lines 82 and 83 into pipe 51 leading to pump 52, and these two lines are supplied with shut off valves 84 and 85 respectively. Conduits 86 and 87 having shut off valves 90 and 91 respectively are connected to pipes 82 and 83, the former con-

duit serving to supply to the system gasoline fractions suitable for reformation while the latter conduit having pump 92 therein connects with the supply pipe line of vapor phase converter 14. An auxiliary pipe line 88 having shut off valve 89 connects conduit 86 with pipe 51 leading to the liquid phase and vapor phase converters. Pipe lines 82 and 83 as well as conduit 87 are heat insulated to prevent heat losses from the products passing therethrough.

In operation, by closing valves 79, 89, 90 and 91 and opening valves 78, 81, 84 and 85, condensate from the bottom of separator 76, such as gasoline fractions suitable for reformation, may be combined with the condensed heavier constituents removed from separator 16, for recycling to either or both of the cracking coils. Or if desirable the condensate from separator 76 may be directed entirely to the vapor phase converter 14 by closing valve 85 and opening 91. Also by properly throttling these two valves the condensate in question may be directed to both pipe 51 and conduit 87 in any proportions selected.

Gasoline fractions suitable for reformation may be injected into either pipe 51 for passage to the liquid phase coil or vapor converter, by opening valve 89—or these fractions may be caused to flow to the vapor phase converter by opening valve 90 and closing 85. Alternatively such fractions may be passed both through pipe 83 and conduit 87 with condensate from separator 76, by opening the proper valves.

Separator 76 may be entirely segregated from the system by closing valves 78, 81 and 84, in which case the valve 79 would be opened to permit the vapors from separator 16 to pass directly to condenser 18 as in Fig. 1.

The added separator and pipe lines serve to supply additional clean products to the vapor phase converter, for cracking at high temperature in the vapor phase. This cracking causes reformation of the gasoline fractions such as to increase the anti-knock value thereof, whereby the anti-knock rating of the product produced by the entire system is increased. Any deficiency in the amount of gasoline fractions withdrawn from the bottom of separator 76 may be made up from an extraneous source represented by conduit 86, or the extraneous source may be used entirely, the separator 76 being isolated from the system by closing valves 78, 81 and 84. In this case the vapors would pass directly from the separator 16 to condenser 18.

Although the invention has been set forth for illustrative purposes as embodying more or less specific details of operation and structural arrangement, it will be understood that many modifications and variations thereof may be made without departing from the spirit and scope of the invention in certain of its aspects. Therefore, only such limitations should be imposed as are indicated in the appended claims.

I claim:

1. The process of converting high boiling hydrocarbon oils into lower boiling products which comprises forcing oil under pressure through a heating coil of restricted cross section wherein the oil is raised to a cracking temperature, delivering the highly heated oil into a body of oil in the first of a plurality of bodies of oil maintained in a plurality of series-connected stills, through which the oil flows in succession, maintaining predetermined cracking temperatures in the respective stills by delivering directly to the body of oil in each still regulated quantities of cracked va-

pors resulting from a vapor phase cracking operation, and withdrawing heavy residue and carbon from the last still of the series.

2. The process of converting high boiling hydrocarbon oils into lower boiling products which comprises subjecting oil to a cracking temperature in transit through a heating coil, delivering the heated oil into the first of a plurality of bodies of oil maintained in a plurality of series-connected stills through which the oil flows in succession, cracking oil in the vapor phase in a separate heating coil, delivering the vapor phase cracked products into the bodies of oil in each of the respective stills to maintain predetermined cracking temperatures therein and crack the bodies of oil in the liquid phase, completing the cracking in the stills and removing the mixed vapors of a liquid phase and the vapor phase cracking operations from the stills, separating out heavier constituents thereof by partial compensation, returning resulting hot condensate to the vapor phase cracking coil to be cracked therein and maintaining superatmospheric pressure upon the oil throughout the operation.

25 3. The process of converting high boiling hydrocarbon oils into lower boiling products which comprises subjecting oil to a cracking temperature in transit through a heating coil, delivering the heated oil into the first of a plurality of bodies of oil maintained in a plurality of series-connected stills through which the oil flows in succession, cracking oil in the vapor phase in a separate heating coil, delivering the vapor phase cracked products into the bodies of oil in each of the respective stills to maintain predetermined cracking temperatures therein and crack the bodies of oil in the liquid phase, completing the cracking in the stills and removing the mixed vapors of the liquid phase and the vapor phase cracking operations from the stills, separating out heavier constituents thereof by partial condensation, returning a portion of the resulting hot condensate to the vapor phase cracking coil to be cracked therein and the rest of said condensate to said heating coil first mentioned, and maintaining superatmospheric pressure upon the oil throughout the operation.

4. The method of converting higher boiling oils into lower boiling oils which comprises heating a confined flowing stream of fresh oil charging stock to cracking temperature under superatmospheric pressure, passing the stream of highly heated oil into an enlarged reaction zone wherein further cracking of the highly heated oil occurs, passing resulting cracked products from said reaction zone into a separate enlarged zone, wherein vapors separate from residue, removing vapors from said zone last mentioned and

subjecting them to fractional condensation to separate vapors of desired boiling range from heavier fractions as condensate, passing condensate so formed through a separate heating zone wherein it is raised to a cracking temperature, introducing resulting highly heated condensate into said enlarged zone second mentioned at a point remote from that at which vapors are removed therefrom, and condensing the fractionated vapors to form a desired distillate.

5. The method of converting higher boiling oils into lower boiling oils which comprises heating a confined flowing stream of fresh oil charging stock to cracking temperature under superatmospheric pressure, passing the stream of highly heated oil into an enlarged zone wherein a cracking temperature is maintained and vapors separate from liquids, passing separated liquids from said enlarged zone into a separate enlarged zone, wherein vapors separate from residue, subjecting resulting cracked vapors to fractional condensation to separate vapors of desired boiling range from heavier fractions as condensate, passing condensate so formed through a separate heating zone wherein it is raised to a cracking temperature, introducing resulting highly heated condensate into said enlarged zone second mentioned at a point remote from that at which vapors are removed therefrom, and condensing the fractionated vapors to form a desired distillate.

6. The method of converting higher boiling oils into lower boiling oils which comprises heating a confined flowing stream of fresh oil charging stock in a heating coil to cracking temperature under superatmospheric pressure, passing the stream of highly heated oil into a primary enlarged zone wherein a cracking temperature is maintained and vapors separate from liquids, passing resulting cracked products from said primary enlarged zone into a second enlarged zone wherein separation of vapors from liquids occurs, preventing the recirculation of liquids thus separated through said heating coil, removing vapors from said second enlarged zone and subjecting them to fractional condensation to separate vapors of the desired boiling range from heavy fractions as condensate, passing condensate so formed through a separate heating zone from which cracked residual oil is excluded wherein it is raised to a cracking temperature, introducing resulting highly heated condensate into said second enlarged zone, preventing the recirculation of cracked residual oil through said separate heating zone, and condensing the fractionated vapors to form a desired distillate.

DONALD H. MACE.

CERTIFICATE OF CORRECTION.

Patent No. 2,072,524.

March 2, 1937.

DONALD H. MACE.

It is hereby certified that error appears in the printed specification of the above numbered patent requiring correction as follows: Page 3, first column, line 55, strike out the word "in"; page 5, first column, line 31, claim 3, for "oil-flows" read oil flows; and second column, line 50, claim 6, strike out "from which cracked residual oil is excluded"; and that the said Letters Patent should be read with these corrections therein that the same may conform to the record of the case in the Patent Office.

Signed and sealed this 30th day of March, A. D. 1937.
